FIG. 2

Des. 174,781

PAGE 3

FIG. 3

FIG. 4

To all whom it may concern:

Be it known that I, Frank J. Sturma, a citizen of the United States, residing at Oklahoma City, Oklahoma County, State of Oklahoma, have invented a new, original, and ornamental Design for a Cattle Feeder, of which the following is a specification, reference being had to the accompanying drawings, forming a part hereof.

Figure 1 is a perspective view looking downwardly at the rear and one side of a cattle feeder showing my new design;

Figure 2 is a perspective view looking downwardly at the front and the other side of the cattle feeder;

Figure 3 is a perspective view similar to Fig. 1, but looking upwardly; and,

Figure 4 is a perspective view similar to Fig. 2 but looking upwardly.

This is a substitute for my application, Serial No. D. 18,294, filed January 30, 1952, now abandoned.

I claim:

The ornamental design for a cattle feeder, as shown.
